United States Patent Office

Des. 202,170
Patented Sept. 7, 1965

202,170

COMBINATION FLOOR MAINTENANCE MACHINE OR THE LIKE

John M. Little and Benjamin G. Bowden, Toledo, and
William O. Bonner, Maumee, Ohio, assignors to The
National Super Service Company, Toledo, Ohio, a
corporation of Ohio

Filed Apr. 15, 1964, Ser. No. 79,509

Term of patent 14 years

(Cl. D9—2)

FIG - 1 -

Des. 202,170

PAGE 2

FIG-2-

FIG-4-

FIG-3-

FIG. 1 is a perspective view showing the front and left side of a combination floor maintenance machine showing our new design;

FIG. 2 is a perspective view showing the rear and right side of the machine shown in FIG. 1;

FIG. 3 is a right side elevational view of the machine shown in FIGS. 1 and 2; and

FIG. 4 is a top plan view on a slightly reduced scale of the machine shown in FIG. 3.

We claim:

The ornamental design for a combination floor maintenance machine or the like, substantially as shown.
